UNITED STATES PATENT OFFICE.

JAMES HARMON BOCK, OF NEW CASTLE, INDIANA, ASSIGNOR OF ONE-HALF
TO MILTON BROWN, OF SAME PLACE.

PRESS.

SPECIFICATION forming part of Letters Patent No. 313,914, dated March 17, 1885.

Application filed February 7, 1883. (No model.)

To all whom it may concern:

Be it known that I, JAMES H. BOCK, a citizen of the United States, residing at New Castle, in the county of Henry and State of Indiana, have invented a new and useful Improvement in Presses, of which the following is a specification, reference being had to the accompanying drawings.

My invention relates to an improvement in presses; and it consists in the peculiar construction and combination of devices, that will be more fully set forth hereinafter, and particularly pointed out in the claims.

In the accompanying drawings, Figure 1 is a front elevation of a press embodying my invention. Fig. 2 is a vertical section taken on the line $\alpha\alpha$ of Fig. 1. Fig. 3 is an elevation of one end of my press. Fig. 4 is a similar view of the opposite end.

20 A represents a platform, which is supported upon the joists a . Sills a' connect these joists and extend along the under side of the platform, and transversely on the under sides of the sills, near their ends, are secured the cleats a^2 , from which extend the vertical standards B, that are mortised into the cleats. A shaft, C, is journaled in these standards near their upper ends, and to one of the projecting ends of this shaft is keyed a wheel, C', that has a 25 series of pins or handles, C², projecting from its outer face. Notches C³ and C⁴ are cut in the edge of this wheel upon opposite sides, and a dog, D, is pivoted in one of the standards and is adapted to enter either of these 30 notches and prevent farther rotation of the wheel and shaft. To the shaft C, on the inner sides of the standards, are secured the eccentric cam-wheels E. A press-box, F, is placed upon the platform between the standards, and is provided with the removable side f and the clamp-yokes f' . Slots b are cut in the standards at a suitable distance above the press-box, and in these slots is journaled a 35 shaft, G, which has a vertical play in the slots. 40 A cog-wheel, H, is keyed to the projecting end of this shaft on the side opposite the wheel C. The outer end of the shaft G passes through the upper end of a block, I. A metallic strap, i , having its rear ends bent to form flanges for 45 bearing on the inner side of the standard and to slide thereon, is secured to the lower end 50

of this block, and in the block is journaled a shaft, K, to which is keyed a pinion, k, for meshing with the wheel H, and an operating-crank, k'. Loops c are placed upon the shaft 55 C, and similar loops, g, are placed upon the shaft G. The loops c and g are connected by the coiled retractile springs L, which serve to keep the shaft G always bearing against the lower sides of the eccentric cam-wheels E. On 60 the edges of these wheels farthest from the shaft C are cut notches e, to receive the shaft G when the press is in the position shown in dotted lines in Fig. 2. An eccentric cam-wheel, G', is keyed to the center of the shaft 65 G, and depending chains o are secured to said shaft near its outer ends, and are adapted to be wound and unwound upon said shaft, and to the lower ends of these chains is suspended the follower O. An anti-friction roller, o', is 70 journaled upon the upper side of the follower, at the center thereof. Vertical guiding-standards f² extend above the fixed side of the press-box. This side of the press-box is provided with braces P, and the removable side thereof 75 has a pivoted brace-hook, R, which enters a staple, r, when the box is closed. Openings p are made in the sides of the press-box, to admit of the insertion of the binding bands, cords, or wires for the bale. Braces S are 80 provided for the standards B.

The operation of my press is as follows: The hay, cotton, or other substance to be pressed is placed in the press-box, the side f closed, and the clamp-yokes f' placed on the upper side of 85 the box at its ends. The crank k' is turned to the left, which causes the suspending-chains to unwind from the shaft G and lower the follower into the press-box, said follower being guided therein by the guiding-standards. When the 90 follower is in place upon the material in the press-box, the cam G' is in a horizontal position. The dog D is released from the notch C³, and the wheel C' is partly rotated by grasping the handles C². As the wheel C' is rotated the 95 cam-wheels E force the shaft G downwardly in the slots in the standards, against the tension of the springs L, and thereby slackens the suspending-chains of the follower. When the 100 wheels C' and E have been given a half-rotation, the dog D enters the notch C⁴ and locks the wheel C' in place, and the shaft G is in

the notches *e* of the cam-wheels *E*. The crank *k'* is then turned to the left, and the cam-wheel *G'* bears upon the anti-friction roller on the upper side of the follower, and forces the follower into the press-box, and forms the bale therein, as will be very readily understood. A dog, *Z*, is provided for locking the wheel *H*, when necessary.

A press thus constructed is adapted for use either as a baling-press for cotton, hay, and similar substances, or for expressing oil, making cider or wine, or other analogous purposes.

Having thus described my invention, I claim—

1. The combination of the press-box, the slotted standards, shaft *C*, having cam-wheels *E*, shaft *G*, journaled in the slots in the standards, having cam *G'* and gear-wheel *H*, pinion *k*, having crank *k'*, springs *L*, and the follower, which is suspended from the shaft *G* by chains or cords, substantially as described.

2. The combination of the press-box, the slotted standards, shaft *C*, having cam-wheels *E*, wheel *C'*, having notches *C³* and *C⁴*, dog *D*, shaft *G*, journaled in the slots in the standards, having cam *G'* and gear-wheel *H*, pinion *k*, having a crank, springs *L*, and the follower, which is suspended from the shaft *G* by chains or cords, substantially as described. 30

3. The combination, with the press-box and the standards, of cam-wheels *E*, shaft *G*, provided with a cam, *G'*, the follower, and cords or chains suspending the latter from the shaft *G*, the cam-wheels *E* revolving against the latter, as set forth. 35

In testimony that I claim the foregoing as my own I have hereto affixed my signature in presence of two witnesses.

JAMES HARMON BOCK.
